UNITED STATES PATENT OFFICE.

ADDISON MIZNER, OF PALM BEACH, FLORIDA, ASSIGNOR TO ADDISON MIZNER, INC.,
OF PALM BEACH, FLORIDA.

DESIGN FOR A CHAIR OR SIMILAR ARTICLE.

Application filed November 10, 1928. Serial No. 28,832. Term of patent 7 years.

To all whom it may concern:

Be it known that I, ADDISON MIZNER, a citizen of the United States, residing at Palm Beach, in the county of Palm Beach and State of Florida, have invented a new, original, and ornamental Design for Chair or Similar Article, of which the following is a specification, reference being had to the accompanying drawing, forming part thereof.

The figure is a perspective view of a chair embodying my new design.

I claim:

The ornamental design for a chair or similar article, as shown.

ADDISON MIZNER.
